UNITED STATES PATENT OFFICE

140,748

DESIGN FOR A CIGARETTE BOX OR SIMILAR ARTICLE

Max L. Goldbert, New York, N. Y.

Application December 27, 1944, Serial No. 117,138

Term of patent 14 years

(Cl. D85—2)

To all whom it may concern:

Be it known that I, Max L. Goldbert, a citizen of the United States of America and a resident of the city, county, and State of New York, have invented a new, original, and ornamental Design for a Cigarette Box or Similar Article, of which the following is a specification, reference being had to the accompanying drawings, in which

Figure 1 is a perspective view of a cigarette box, or similar article, with the covers in closed position, showing my new design;

Fig. 2 is a side elevational view thereof with the covers in closed position;

Fig. 3 is an end elevational view thereof with the covers in closed position;

Fig. 4 is a top plan view thereof, with the covers in closed position;

Fig. 5 is a side elevational view similar to Fig. 2, with the covers swung upwardly of the box; and

Fig. 6 is a section on the line 6—6 of Fig. 4, showing the bevel of the cover.

I claim:

The ornamental design for a cigarette box or similar article, as shown.

MAX L. GOLDBERT.
